FIG. 7

FIG. 8

UNITED STATES PATENT OFFICE.

SHERWOOD M. CHASE, OF COLUMBUS, OHIO, ASSIGNOR TO THE CHASE FOUNDRY & MFG. COMPANY, OF COLUMBUS, OHIO, A CORPORATION OF OHIO.

RAYON TRUCK.

Application filed September 14, 1928. Serial No. 305,958.

This invention relates to stretchers for rayon silk.

It is the custom in handling skeins of rayon silk to support them on bars formed of aluminum tubes and to support the skein and bars 5 assembled on a rack for the purpose of drying the rayon silk. The rack on which the aluminum bars have uniformly heretofore been supported have been made of iron or 10 some other similar material that would cause the aluminum skein bars to become roughened and damage the rayon silk which came in contact with the roughened places.

It is the purpose of this invention to provide a rack for the support of the skein bars 15 in such a way that the bars will not become lacerated and torn so as to damage the threads supported thereby.

It is the particular object of this invention 20 to provide a frame for supporting the aluminum bars carrying the skeins of thread on which there are provided supplemental cushion members made of soft and yielding material to immediately support the aluminum skein bars.

This is accomplished by providing the frame bars with a cushion surface of some other material than steel or iron. The other material used may be aluminum, copper, 30 brass, or fibrous material formed in such a way as to form retaining means for the skein bars.

For the purpose of illustration there is presented herewith in the drawings a preferred 35 embodiment of this invention, which is shown by way of illustration and to which the invention is not intended to be limited.

Fig. 1 is a side view of a truck showing a plurality of means for supporting and 40 stretching skeins of rayon silk.

Fig. 2 is an end view with part of the operating means broken away.

Fig. 3 is a section of one of the stretcher bars showing the cushion plates attached thereto.

Fig. 4 is a cross section of Figure 3 on line 4-4.

Fig. 5 is a cross section of Figure 3 on line 5-5.

Fig. 6 is a view showing one end of one of the cushion bars.

Fig. 7 is a view showing one of the skeins of thread and its skein bars.

Fig. 8 is a section on line 8-8 of Fig. 1. The device which is the subject matter of

this application is fully shown in Fig. 1 mounted upon a truck. This truck may be rolled from place to place and is adapted to be used for conveying the silk into some drying oven.

The reference numeral 1 is used to designate the base of the truck while the rollers that support the truck are indicated by the numeral 2.

The base of the truck is rectangular in 65 shape and has extending upwardly therefrom at each corner upright posts indicated by the numeral 3, which are adapted to support the stretching and supporting means for the skeins of rayon silk thread.

Extending across the upper ends of the upright post at each end of the truck is a cross beam or bar indicated by the numeral 4, which tends to hold the upper ends of the posts.

There are shown in this drawing two sets of stretching and holding means for the skeins of thread. Each set is composed of similar parts located on each side of the frame. The stretching means is composed 80 essentially of two bars extending longitudinally over the truck frame on each side of the truck. The upper bar is fixed to the frame and is indicated by the numeral 5. These bars are attached to the uprights of 85 posts 3 by means of bolts or rivets indicated by the numeral 6.

Associated with each fixed stretcher bar is a movable bar indicated by numeral 7, which is supported beneath the fixed bar and guided 90 in slots formed by the guide bars 8 and the uprights 3. Just beneath each one of the fixed bars and attached to the upright post 3 are brackets 9, which have extending therefrom ears indicated by the numeral 10 by 95 which the brackets are attached to the upright posts. The lower ear of each of these brackets serve to space the guide bar 8 from the upright for the accommodation of the movable stretcher bars. The lower ends of 100 the guide bars 8 are attached to the upright by means of rivets 11.

It is understood that the guide bars 8 provide guiding slots for both upper and lower movable stretcher bars. There are two sets 105 of the brackets 9, each having a bracket attached to each one of the uprights.

In each of the side pairs of brackets there extends a hand wheel shaft indicated by the numeral 12, which is located in the brackets 110

9 so as to have up and down movement therein. On one end of each of the hand wheel shafts on one side of the frame is a hand wheel indicated by the numeral 13, while on the other end of each of the four hand wheel shafts is a sprocket wheel indicated by numeral 14. Connecting the two upper sprocket wheels and the two lower sprocket wheels are sprocket chains indicated by the numeral 15. 10 By means of this sprocket wheel and chain construction each shaft of the upper set or the lower set of stretching members may be operated by turning one of the hand wheels 13. Each of the hand wheel shafts are threaded 15 as indicated by the numeral 16 and receive thereon in threaded relation therewith nuts 17.

Extending from each side of the nut are ears 18 to each of which is pivotally attached 20 a link 19, the other end of which link is attached to the stretcher bars 5 or to the stretcher bars 7. The hand wheel shaft is located between a fixed bar and a movable bar and has a toggle connection therewith by 25 means of the nuts 17 and the links 19 by which the stretcher bars may be moved to or from each other. Each end of the hand wheel shaft has at least two screw thread sections in which the threads are in different directions so that in the turning of the shaft the 30 nuts thereon will move toward or from each other. When the nuts are caused to move toward each other the stretcher bars are separated and when they are caused to move from each other the stretcher bars are made 35 to approach each other.

The stretcher bars 5 and 7 are composed of such material as steel or iron and are adapted to have strength and rigidity. For 40 the purpose of providing a soft and smooth surface for receiving and carrying the skein bars there is provided a cushion bar or a series of cushion bars indicated by the numeral 20. These bars may be made in section and are 45 shown here as composed of 6 sections for each stretcher bar. These cushion sections are attached to the stretcher bars by means of rivets or bolts indicated by the numeral 21. The bearing surface of these cushion bars is 50 scalloped or serrated in form; as at 22, providing cavities in which the skein bars 23 may rest.

This device is used in connection with skeins 55 of thread 24 which is supported by the skein bars. There are two bars for each skein of thread. One pair is supported by the upper stretcher bar while the other pair is beneath the movable stretcher bar and is adapted to seat in one of the notches therein. When the 60 proper number of skeins and the skein bars have been assembled on the stretching device the hand wheel is rotated so as to bring the nuts on each part of the hand wheel shaft toward each other, thereby spreading the stretcher bars apart and stretching the rayon 65

silk carried thereby on the skein bars. When the rayon silk has been thus assembled and properly tensed the truck with the rayon silk thereon may be conveyed by the rollers to any suitable place for drying or other purpose. It 70 has been found in actual practice that this stretching device with the cushion bars is very effective in that it does not cause the skein bars to become lacerated or roughened so that the silk is damaged. 75

Having thus described my invention, what I wish to protect by Letters Patent and claim as new, is set down in the following claims:

1. In a device of the class described, a support, a plurality of stretcher bars carried by said support, means for moving said bars to and from each other, and a protective cushion member provided for each stretcher bar. 80

2. In a device of the class described, a support, a plurality of fixed stretcher bars carried by said support, a plurality of movable stretcher bars associated with said support, one movable bar being associated with each fixed bar, means for moving the movable bar to and from the fixed bar, and a protective 85 cushion member associated with each bar. 90

3. In a device of the class described, a support, a plurality of fixed stretcher bars supported by said support, a plurality of movable stretcher bars associated with said support, one movable bar being associated with each fixed bar, means to move the bars to and from each other, and a series of soft metallic cushion members attached to each bar. 95

4. In a device of the class described, a support, a plurality of fixed stretcher bars carried by said support, a plurality of movable stretcher bars associated with said support, one movable bar being associated with each fixed bar, and a corrugated cushion member 100 attached to each stretcher bar. 105

5. In a device of the class described, a pair of fixed stretcher bars, a pair of movable stretcher bars, means connecting each fixed stretcher bar with one of the movable bars to move them to and from each other, and a corrugated plate or corrugated cushion member 110 of soft material attached to each bar. 115

6. In a device of the class described, means for supporting a series of aluminum skein bars with thread thereon, said means including a pair of movable bars, a pair of fixed bars and means on each bar to provide a seat for the aluminum bars so that the aluminum bars will not become lacerated or torn. 120

7. In a support, in combination with a plurality of aluminum skein bars with thread thereon, means for supporting the bars and stretching the thread, including a pair of fixed bars, a pair of movable bars, and an 125 aluminum cushion member attached to each bar and adapted to engage and support said skein bars.

8. In a support, in combination with a plurality of aluminum skein bars, means for 130

supporting said bars, said means including a plurality of support bars and a corrugated cushion member attached to each of said supports.

9. In a support, in combination with a plurality of aluminum skein bars, means for supporting said bars, said means including a plurality of support bars and a corrugated aluminum cushion member attached to each 10 of said supports.

10. In a support, in combination with a plurality of aluminum skein bars with thread thereon, means for supporting the bars and stretching the thread, including 15 a pair of fixed bars and a pair of movable bars, an aluminum cushion member on each fixed bar and movable bar and adapted to support and hold the skein bars in spaced relation to each other and 20 means for moving the fixed and movable bars to and from each other.

11. In a support, in combination with a plurality of soft metal skein bars, corrugated

soft metal bars adapted to support said skein bars and means to adjustably support said 25 corrugated bars.

12. In a support, in combination with a plurality of soft metal skein bars with thread thereon, a plurality of fixed corrugated soft metal supporting bars, a plurality of movable 30 corrugated soft metal bars, said corrugated bars being adapted to seat and support said skein bars, and means to move the movable bars from the fixed bars to stretch the thread 35 on the skein bars.

13. In a support, in combination with a plurality of soft metal skein bars with thread thereon, a pair of fixed corrugated soft metal supporting bars, and a pair of 40 movable corrugated soft metal bars for supporting said skein bars and means for moving the movable pair of bars from the fixed pair of bars to stretch the thread.

In testimony whereof, I affix my signature.

SHERWOOD M. CHASE.
